UNITED STATES PATENT OFFICE.

HARTLEY A. CABLES, OF PHILADELPHIA, PENNSYLVANIA.

NECK-WEAR.

SPECIFICATION forming part of Letters Patent No. 314,794, dated March 31, 1885.

Application filed June 16, 1884. (No model.)

To all whom it may concern:

Be it known that I, HARTLEY A. CABLES, a citizen of the United States, residing at Philadelphia, in the county of Philadelphia and State of Pennsylvania, have invented certain new and useful Improvements in Neck-Wear, of which the following is a specification.

My invention is a support for neck ties, scarfs, and like articles of neck-wear; and it consists of a band adapted to clasp the collar-band and extend back beneath the coat or vest of the wearer, and to support the tie or scarf in its position without tilting, and permit its ready application and detachment.

15 My invention further consists in constructing the support of combined elastic and non-elastic material, so as to secure the desired clasp effect in a very cheap structure.

In the drawings, Figure 1 is a perspective view showing a neckscarf with my improvement. Fig. 2 is a perspective view showing the improvement as applied in connection with a bow. Fig. 3 is a plan view showing the same applied to a collar. Figs. 4, 5, 6, 25 and 7 are perspective views illustrating different modes of making the support of combined elastic and non-elastic material. Fig. 8 is a view illustrating a connecting-button; Fig. 9, a view of part of the shirt-band.

30 The supporter consists of a spring-band, A, of metal or other elastic material, or paper, card-board, or other non-elastic material, combined with an elastic strip. In either case the band in its normal shape is curved, so that when applied to the neck it will lie closely against or clasp the band of the shirt and extend back to such a distance as to be covered by the vest or coat.

The bow, tie, or scarf B is secured to the 40 center of the band in any suitable manner, and the band is covered with the same material as the tie, so that when the article is in position upon the neck of the wearer the covered band will have the appearance of a scarf 45 passing completely around the neck.

Any suitable fastening device is used for securing the article in place, a preferable attachment being a button, C, with a head, a, and flat stem b, and terminal catch c, adapted 50 to engage with a socketed plate, D, secured to the band, so that the latter may be fastened to

the band of the shirt by passing the stem b through the button-hole a, and then introducing the end of the stem or catch into the socket.

The extended band A, clasping the shirt band or collar, and held in place by the button or any suitable connection, affords a steady support for the tie or scarf, which is thus retained in its proper position, while the movements of the wearer are in no way restricted, and the article may be readily detached and replaced in proper position without disturbing the clothing.

Where the band is to support only a tie or bow, as in Fig. 2, it consists simply of a strip of uniform width; but where it is used for the support of a scarf it is preferably provided with a shield, d, to which the body of the scarf is connected in any suitable or ordinary manner.

In order to secure the clasp effect of the band, and at the same time manufacture the article cheaply, I prefer to make the band, or band and shield combined, of stiff card-board or paper, and to connect thereto a strip, f, of metal, rubber, or other elastic material, bent so as to spring naturally to a curved form.

In Fig. 4 a flat strip of brass is shown as applied to a pasteboard shield, d, having arms or extensions constituting the band A. In Fig. 5 said shield and band are shown combined with a wire, which imparts the desired curved form and spring action. In Figs. 6 and 7 a pasteboard shield is shown connected to a curved strip of brass.

The pasteboard and metal portions of the device may be connected together in any suitable manner by cement, sewing, riveting, or otherwise. When a flat strip of brass is used, 90 it may be slit at intervals to form tongues i, which are bent outward and forced through the pasteboard and clinched, as shown in Figs. 4 and 7. When a wire is employed, it may be passed from one side to the other through the 95 card-board, as shown in Fig. 5.

By the construction described I avoid the difficulties incident to the use of the ordinary necktie-supporting shields, which are apt to become displaced or to assume an angle to the 100 neck, which is prevented in my improved device by the use of the extending clasping-arms

of the band, which not only prevent any such tilting, but are held in position by the pressure of the vest or coat.

Without limiting myself to the precise construction and arrangement of parts shown, I claim—

1. A supporter for neck-wear, provided with a spring-band adapted to support the tie or scarf at the front, and extended back on each side beyond the tie around the collar-band to clasp with its ends the sides of the collar, substantially as set forth.

2. A supporter for neck-wear, consisting of a spring-band having its ends extending beyond the tie or scarf to about midway around the sides of the shirt-band or collar, and bent to fit and clasp with its ends the sides of the band or collar, substantially as set forth.

3. The combination, in an article of neck-wear, of a curved elastic band extending to and adapted to clasp with its ends the sides of

the collar-band, a bow or scarf connected to the center of said elastic band, the latter being covered with the same material as the bow or scarf, substantially as set forth.

4. The combination, in a support for neck-wear, of a strip of card-board or other non-elastic material supporting the bow or scarf at the center and extending to the sides of the collar-band, and a strip of thin metal or other material connected to the said strip of card-board and curved to maintain the latter in a curved form to clasp the shirt or collar band, substantially as specified.

In testimony whereof I have signed my name to this specification in the presence of two subscribing witnesses.

HARTLEY A. CABLES.
